[57] CLAIM

The ornamental design for a combined watch housing and bezel therefor, as shown and described.

DESCRIPTION

FIG. 1 is a top plan view of a combined watch housing and bezel therefor showing our new design;

FIG. 2 is a bottom plan view thereof;

FIG. 3 is a right side elevational view thereof;

FIG. 4 is a left side elevational view thereof;

FIG. 5 is a front elevational view thereof, the rear being a mirror image thereof;

FIG. 6 is a top plan view of another embodiment of our new design of FIGS. 1-5;

FIG. 7 is a bottom plan view thereof;

FIG. 8 is a right side elevational view thereof;

FIG. 9 is a left side elevational view thereof; and

FIG. 10 is a front elevational view thereof, the rear view being a mirror image.
